(57) **CLAIM**

The ornamental design for a phone plug connector, as shown and described.

DESCRIPTION

FIG. 1 is a front-end view of a first embodiment of the phone plug connector of the invention;

FIG. 2 is a side view of the phone plug connector of FIG. 1, the opposite side view being identical;

FIG. 3 is a top plan view of the phone plug connector of FIG. 1, the opposite bottom plan view being identical;

FIG. 4 is a front-end view of a second embodiment of the phone plug connector of the invention;

FIG. 5 is a side view of the phone plug connector of FIG. 4, the opposite side view being identical; and,

FIG. 6 is a top plan view of the phone plug connector of FIG. 4, the opposite bottom plan view being identical.

No claim is made to the ornamental appearance of the back end, which receives the cable (shown in phantom) for either the first or second embodiment.
